UNITED STATES PATENT OFFICE

155,550

DESIGN FOR A VACUUM CLEANER

Frederick K. Storm, Jr., Los Angeles, Calif., assignor to Filtex Corporation, Los Angeles, Calif., a corporation of Michigan

Application November 1, 1948, Serial No. 149,422

Term of patent 14 years

(Cl. D9—5)

To all whom it may concern:

Be it known that I, Frederick K. Storm, Jr., a citizen of the United States, residing in Los Angeles, in the county of Los Angeles and State of California, have invented a new, original, and ornamental Design for a Vacuum Cleaner, of which the following is a specification, reference being had to the accompanying drawings, forming a part thereof, in which:

Figure 1 is a side elevation of a vacuum cleaner, showing my new design;

Figure 2 is a top plan view thereof;

Figure 3 is a bottom plan view thereof;

Figure 4 is an end elevation of the left hand end of Figure 1; and

Figure 5 is an end elevation of the right hand end of Figure 1.

I claim:
The ornamental design for a vacuum cleaner, as shown.

FREDERICK K. STORM, JR.
